UNITED STATES PATENT OFFICE

2,416,644

SAFETY PIN

Raymond R. Rundell, Miami, Fla.

Application July 6, 1944, Serial No. 543,663

4 Claims. (Cl. 24—150)

1

This invention relates to safety pins.

An object of this invention is to provide in a safety pin means for locking the pin element in closed position.

Another object of this invention is to provide a safety pin including a keeper which is so arranged and constructed that when the pin element is normally engaged with the keeper, the pin element will not be locked, but when the back bar of the device is bent or bowed inwardly the point of the pin will be shifted endwise to a position confronting the locking means, and release of the bowed back will result in the point of the pin element moving endwise into the locking means therefor, so that the pin element will be locked against normal pressure tending to release the same from the keeper.

To the foregoing objects and others which may hereinafter appear the invention consists of the novel construction, combination and arrangement of parts as will be more specifically referred to and illustrated in the accompanying drawing, wherein are shown embodiments, but it is to be understood that changes, modifications and variations may be resorted to which fall within the scope of the invention as claimed.

In the drawings:

Figure 1 is a detail side elevation of a safety pin constructed according to an embodiment of this invention,

Figure 2 is a view similar to Figure 1, but showing the device with the pin released from the locking means embodied in the keeper,

Figure 3 is a fragmentary plan view of the device,

Figure 4 is a sectional view taken on the line 4—4 of Figure 3,

Figure 5 is a sectional view taken on the line 5—5 of Figure 1,

Figure 6 is a fragmentary plan view of a modified form of this invention,

Figure 7 is a fragmentary sectional view taken on the line 7—7 of Figure 6,

Figure 8 is a fragmentary side elevation partly in section of another modification of this invention,

Figure 9 is a fragmentary plan view of another modification of this invention.

Figure 10 is a sectional view taken on the line 10—10 of Figure 9,

Figure 11 is a fragmentary top plan of a further modification, and

Figure 12 is a sectional view taken on the line 17—17 of Figure 16.

Referring to the drawings, the numeral 10

2

designates an elongated resilient back bar and the numeral 11 designates generally a pin which is integral with the back bar 10, being connected therewith by means of a coil 13. The free end 5 of the back bar 10 is gripped or otherwise firmly secured to a keeper, generally designated as 12.

The keeper 12 includes a U-shaped keeper member 14 which is spaced from the back bar 10 and extends inwardly in the direction of the point 15 of the pin member 11. The keeper 12 includes a centrally disposed divider 16 which extends from the rear portion 17 of the keeper and is positioned between the opposite sides of the U-shaped keeper member 14. The keeper member 15 at a point outwardly from the inner end thereof is formed with an inwardly offset detent 18 which opens inwardly, the bight 19 of the keeper member 14 being cut, as indicated at 20, so that the detent 18 will open or face inwardly 20 in order that the terminal end of the point 15 may be positioned on the outer side of the detent 18 being extended through the opening 20, as shown in Figure 4.

In order to provide for the extension of the point 15 into the locking member or detent 18, it is necessary, as shown in Figure 2, to bend or bow the back bar 10 inwardly with the pin 11 engaged within the keeper member 14. With the point 15 bearing against the inner side of the bight 19 of the keeper member 14 and the back bar 10 bowed inwardly, the terminal end of the point 15 will be positioned inwardly from the inner edge of the detent or locking member 18, as shown in Figure 2.

35 The back bar 10 may be released then and the return of the back bar 10 to its normal configuration, which is the configuration shown in Figure 1, will provide for the endwise movement of the pin 11 outwardly until the point 15 engages within the concave outer side of the detent or locking member 18. In this position which is the position shown in Figure 4, the pin 11 is locked against inward movement by the detent or locking member 18 and is locked against outward movement by the bight 19 of the keeper member 11.

Referring now to Figures 6 and 7, there is disclosed a keeper member 21 which is identical 50 with the keeper member 12. In this modified form of the invention, the keeper element 22 has struck inwardly from the bight thereof an inwardly bowed or bent strip 23 constituting the locking member. The strip or locking member 23 is struck inwardly by cutting the bight of the

55 23 is struck inwardly by cutting the bight of the

keeper element 22, as indicated by the numerals 24 and 25.

The pin 26 is adapted to have the point 27 thereof extending transversely across the concave outer side of the locking member 23, as shown in Figure 6, with the terminal end of the point 27 extending slightly beyond and outwardly of the edge 24. The terminal end of the point 27 will be positioned on the inner side of the bight of the keeper element 22 so that the point will not stick into any clothing or the like.

The pin 26 is engaged with the locking member 23 in the same manner as the engagement of pin 11 with locking member or detent 18, that is, by bowing of the back bar inwardly so as to move the pin 26 endwise until the point thereof is positioned inwardly of the inner edge of the inwardly offset locking member 23.

Referring to Figure 8, the numeral 28 designates generally a keeper structure with which a pin 29 is adapted to be engaged. The keeper structure 28 is U-shaped in transverse section and the bight 30 of the keeper has a lug 31 struck inwardly therefrom with the lug 31 provided with an opening 32. The point of the pin 29 is adapted to engage within the opening 32 as shown in Figure 8.

Referring now to Figures 9 and 10, the numeral 33 designates generally a U-shaped keeper with which a pin 34 is adapted to be engaged. The keeper 33 has struck from the bight 35 thereof a pin locking member 36. This pin locking member 36 is struck from one side of the bight 35 and is then bent inwardly and provided with a concave outer side 37 forming a seat for the pin 34.

Referring now to Figures 11 and 12, there is disclosed a further modified form of keeper and locking means for the pin. In this form the keeper 58 has struck inwardly from the bight 59 thereof a pin locking member 60. The pin locking member 60 extends lengthwise of the adjacent side of the keeper 58 having its free end 61 innermost and the opposite sides 62 of the locking members cut away from the adjacent portions of the bight 59. The outer side of the locking member 60 is concave, as shown in Figure 12, so as to provide a seat with which the point of the pin 63 may be engaged.

In the pin locking structures shown in Figures 9 and 11, the free edge or edges of the locking members 36 and 60, respectively, are spaced from the adjacent portion of the keepers 33 and 58,

respectively, a distance sufficient so that the pins 34 and 63 may be inserted in the locking members from the side or sides of the locking members without banding or distortion of the pin, or with only slight distortion of the latter. These pin locking constructions therefore provide a second means whereby the point of the pin may be inserted in the locking member.

In the constructions shown in Figures 9 and 11 the pin can be unlocked by lateral movement of the pin, or by the longitudinal bending thereof.

What I claim is:

1. A safety pin comprising an elongated resilient bar, a pin, a resilient coil integral with adjacent ends of said bar and said pin, a U-shaped keeper fixed to said bar at the end thereof opposite from said coil and having a terminal portion of U-shaped cross section having side arms and a bight, the bight and side arms of said keeper embracing said pin and a pin locking member between said arms overlying the point of said pin whereby the point of said pin can only be released from said locking member by endwise movement of said pin effected by longitudinal bending of said bar.

2. A safety pin as set forth in claim 1 wherein said locking member inter-connects said arms.

3. A safety pin as set forth in claim 1 wherein said locking member is elongated and is formed with parallel free opposite longitudinal edges and a free inner end.

4. A safety pin as set forth in claim 1 wherein said locking member is integral at one lengthwise edge with said keeper.

RAYMOND R. RUNDELL.
